(57) **CLAIM**

The ornamental design for a remote controller for earphones, as shown and described.

DESCRIPTION

FIG. 1 is a front view of a remote controller for earphones showing our new design;

FIG. 2 is a rear view thereof;

FIG. 3 is a left side view thereof;

FIG. 4 is a right side view thereof;

FIG. 5 is a top plan view thereof; and,

FIG. 6 is a bottom view thereof.

The broken lines shown are included for the purpose of illustrating the unclaimed portions of a remote controller for earphones and form no part of the claimed design.
